(57) **CLAIM**

The ornamental design for an outdoor insect bait station, as shown and described.

DESCRIPTION

FIG. 1 is a perspective view from above of an outdoor insect bait station showing our new design;

FIG. 2 is a perspective view from below thereof;

FIG. 3 is a side elevational view thereof;

FIG. 4 is a side elevational view thereof rotated 90° with respect to the view in FIG. 3;

FIG. 5 is a top plan view thereof; and,

FIG. 6 is a bottom plan view thereof.

The broken line showing of environment in the drawings is for illustrative purposes only and forms no part of the claimed design.
